UNITED STATES PATENT OFFICE.

ROBERT C. ROSENBERG, JR., OF SAN FRANCISCO, CALIFORNIA.

UNLOADING MACHINE FOR RAILROAD CARS AND THE LIKE.

Application filed December 12, 1921. Serial No. 521,717.

To all whom it may concern.

Be it known that I, ROBERT C. ROSENBERG, Jr., a citizen of the United States, residing at San Francisco, in the county of San Francisco and State of California, have invented new and useful Improvements in Unloading Machines for Railroad Cars and the like, of which the following is a specification.

10 This invention relates to an unloading machine for railroad cars and the like.

The principal object of this invention is to provide a portable car-unloading machine equipped with an endless conveyor provided 15 with spaced material carrying buckets adapted to be manually adjusted to various working positions so as to reach and remove practically all material from open top cars, such as gondola cars.

20 Another object of this invention is to provide convenient means associated with the machine and adapted to compensate for varying widths of cars and also serving to steady and balance the machine on the car to 25 be unloaded.

A further object of this invention is to provide a machine for rapidly unloading cars, which is simple in construction, and light enough to be shifted from one car to 30 another through the provision of improved means, and a machine which will require only the services of a single operator to accomplish the unloading of the car.

35 A further object of this invention is to provide means cooperating with the endless conveyor adapted to retain the said conveyor in an adjusted position.

Other objects and advantages will be apparent during the course of the following 40 description.

In the accompanying drawings forming a part of this specification, and in which like numerals are employed to designate like parts throughout the same,

45 Fig. 1 is an end elevation of a gondola car with my invention being mounted thereon,

Fig. 2 is a diagrammatic view disclosing the angular movements of the conveyor on one side of the car,

50 Fig. 3 is a diagrammatic view disclosing the angular movements of the conveyor on the opposite side of the car.

Fig. 4 is a detail side elevation of a gondola car with the machine being shown in 55 front elevation.

Fig. 5 is a vertical section through the car

with the machine being shown thereon partly in elevation and partly in section,

Fig. 6 is an end elevation of the conveyor supporting means forming a part of my invention,

Fig. 7 is a horizontal section through a part of the table, and supporting means the view being taken on the line 7—7 of Fig. 6,

Fig. 8 is a detail plan view of the upper end boom showing to advantage the upper sprocket for the elevating chain,

Fig. 9 is a plan view of the lower end of the boom, showing to advantage the lower sprocket for the elevating chain,

Fig. 10 is a detail view showing a pawl and ratchet forming a part of my invention, and the supporting means therefor, the view being taken on the line 10—10 of Figure 11,

Fig. 11 is a sectional detail of the same, the view being shown on the line 11—11 of Figure 10, and

Fig. 12 is a side elevation of the means for transferring the machine from one car to another.

In the accompanying drawings wherein for the purpose of illustration is shown a preferred embodiment of my invention, the reference character A designates a gondola car, B the machine as a whole and C a truck or any suitable wheeled vehicle which is adapted to receive material unloaded from the body of the gondola car.

The machine per se includes a frame 15 extending parallel to the upper edge of one wall D of the car and is provided with a pair of double flanged wheels 16 adapted to rest on the upper edge of the side wall D.

Connected to the frame by brace rods 17, is a turn table indicated as a whole by the numeral 18. This turn table has centrally disposed therein a tubular standard 19 and has likewise provided supporting bars 20 which have connected to their upper extremities a yoke 21.

Secured to the frame 15 and extending beneath the turn table is a cross arm 22 which terminates in a sleeve 23 adapted to receive therein a shaft 24 which has mounted on its outer extremity a double flanged wheel 25 and on its inner extremity a collar 26, which serves to prevent the shaft 24 from being disengaged from the sleeve 23.

It is manifest by this construction, that the wheel 25 is adapted to ride on the upper edge of the side wall E of the car and this positioning of the wheel and the two oppo-

site wheels 16 serves to balance the machine on the top of the car. The construction of the shaft 24 and the collar 26 compensates for varying widths of cars and thus makes the machine applicable to various types of gondola cars.

Angle irons 26' and 27 are connected to the yoke 21 adjacent the lower extremity thereof and have secured thereto a platform adapted to support a motor 28, which is the medium through which the machine is driven. This platform is braced by tie rods 29 which are suitably connected to the yoke 21. As shown to advantage in Figures 1 and 15 6, it will be observed that a shaft 30 is journaled in the upper extremities of the yoke and supports a sprocket wheel 31 which has trained thereover a portion of an endless chain 32 which carries a plurality of spaced 20 material receiving buckets 33. Pivotaly secured on the shaft 30 is a channel beam 34 which has disposed in its lower bifurcated extremity a shaft 34' provided with a lower sprocket wheel 35 over which the chain 32 25 is also trained. Connected to the motor 28 is a drive shaft 36 having mounted on its free end a beveled gear 37 adapted to mesh with a gear 38. This gear upon its rotation is adapted to drive a chain belt 39 which in 30 turn is trained over a driving sprocket wheel 40 mounted adjacent one extremity of the shaft 30 and adapted to rotate the same for the purpose of driving the chain 32.

The numeral 41 designates a hopper 35 adapted to be positioned in close proximity to the yoke 21 so as to receive the material conveyed from the bottom of the car and carried by the buckets 33. This hopper has detachably secured thereto a telescoping 40 funnel 42 provided with a flexible connection 43 receivable on the lower end of the hopper, so that the funnel may be adjusted to various angular positions and thus proportionately distribute the load in the bottom 45 of the conveyor C.

As shown to advantage in Figure 5 I have pivotally connected one extremity of a supporting arm 43' to one of the braces 20 and have integrally formed with this supporting arm a slotted quadrant or lever 44 through which extends a shaft 45, adapted to be operated by a hand wheel 46. From the beam 34 there depends a hanger 46^a through which the shaft 45 extends, while 55 cooperating pinions 46^b mesh with racks 46^c formed integral with the slotted quadrant 44. These pinions are likewise mounted on the shaft 45 and by their actuation, through the medium of the hand wheel 46, serve to 60 elevate or lower the conveyor with relation to the body of the car. On the shaft I have also positioned a control ratchet 47 cooperating with a pawl 48 pivoted on the quadrant 44 for the purpose of retaining the conveyor 65 in an adjusted position.

From this construction it will be obvious that the conveyor can be angularly elevated to different heights in the car, and from a consideration of the diagrammatic views as illustrated in Figures 2 and 3 it will be 70 obvious that the conveyor can be shifted from one side of the cross arm 22 to the other side of the same, with the motor always in the same position relative to the yoke. Thus I have avoided the necessity of 75 providing means for shifting the machine crosswise of the car and have disclosed novel construction whereby the buckets of the conveyor may be brought into contact with material in all parts of the gondola car for 80 rapidly unloading the same.

When it is desired to retain the wheels 16 in alignment it is only necessary to insert locking pins 50 in discs 50' of the wheel brackets and thus there will be no danger 85 of the wheels being displaced from the top walls of the car.

In Figure 12 there has been disclosed 90 means for transferring the machine from one car to the other and this means includes a cross bar 51 equipped with pivoted inclined extremities 52 and 53 over which the respective flanged wheels of the machine ride when the apparatus is being transferred from one car to another.

It is to be understood that the form of 95 my invention herewith shown and described is to be taken as a preferred example of the same, and that various changes in the shape, size and arrangement of parts may be 100 resorted to without departing from the spirit of the invention or the scope of the subjoined claims.

Having thus described my invention, I 105 claim:—

1. A machine of the character described adapted to rest and travel upon the top of the walls of a car, said machine comprising a supporting frame, a turn table connected to said frame, a vertical standard positioned in said turn table, a yoke connected to said standard, endless conveying means for receiving the material in the car and delivering the material outside the car, mechanism for actuating said conveying means, means for adjusting the conveyor to retain the same in a fixed receiving and delivering position, and means connected to said turn table for compensating for various widths of cars so that the machine may be balanced thereon, said means including a cross arm provided with a sleeve, and a shaft longitudinally movable in said sleeve.

2. A machine of the character described adapted to rest and travel upon the top walls of the car, said machine comprising a supporting frame, a turn table connected to said frame, a vertical standard positioned in said turn table, a yoke connected to said standard, an endless conveying means for 130

receiving the material in the body of the car and delivering the material outside the car, a platform disposed in a plane parallel to the plane in the top of the car and connected to said yoke, a motor disposed on said platform, and mechanism connected to said motor and conveying means for actuating the latter.

3. A machine of the character described
adapted to rest and travel upon the top walls
of the car, said machine comprising a sup-
porting frame, a turn table connected to said
frame, a vertical standard positioned in said
turn table, a yoke connected to said stand-

ard, an endless conveying means for receiv- 15
ing the material in the body of the car and
delivering the material outside the car, a
platform disposed in a plane parallel to the
plane of the top of the car and connected
to said yoke, a motor disposed on said plat- 20
form, mechanism connected to said conveyor
and adapted to actuate the same, said mecha-
nism including a driving shaft, a chain drive,
a driving sprocket, and a main shaft driven
by said driving sprocket. 25

In testimony whereof I, affix my signature.

ROBERT C. ROSENBERG, JR.
